UNITED STATES PATENT OFFICE.

HENRY M. SHEER, OF QUINCY, ILLINOIS.

OIL CONTROL FOR BURNERS.

Application filed June 13, 1925. Serial No. 36,912.

To all whom it may concern:

Be it known that I, HENRY M. SHEER, a citizen of the United States, residing at Quincy, in the county of Adams and State 5 of Illinois, have invented certain new and useful Improvements in Oil Controls for Burners, of which the following is a specification.

My present invention relates to an improvement in oil controls for burners.

The present invention comprises a tandem float for automatically controlling the flow of oil in oil-burning heaters. The object of the tandem float is to maintain at all times an exact oil level at the proper place, regardless of how much and in what direction the heater is tilted. The point where the exact oil level must be maintained is, of course, the burner. If the oil varies at the burner, or if the oil pressure varies at the valve that controls the oil to the burner, the flame will vary accordingly. For this reason, and to accomplish the results desired, the float control valve preferably should be located directly beneath the burner, and the needle valve controlling the flow of oil to the burner preferably should be directly below the burner. The best known way in which the foregoing assembly can be secured is to employ two floats in tandem, pivotally connected with and supporting a connecting bar, to which bar a valve is connected which is operated by both floats through the medium of the connecting bar.

In the accompanying drawings:

Fig. 1 is a view in elevation with a portion broken away;

Fig. 2 is a vertical section on the line 40 2-2 of Fig. 1;

Fig. 3 is a similar view showing the device as applied; and

Fig. 4 is a perspective view of the float connecting bar.

The oil chamber preferably consists of two parts 1 and 2, preferably of cast metal having flanges around their edges and held together by screws or bolts 3, with a suitable packing or gasket (not shown) between the flanges.

The numeral 4 represents two oil cups having the floats 5 therein. These floats are adjustably and removably connected with rods or wires 6, and the latter are pivotally connected at their lower ends with the con-

necting bar 7, which latter is suspended or sustained by the floats. The chamber formed in the parts 1 and 2 communicates with the cups 4, and forms a float chamber which extends into both of the cups 4 insuring that the oil levels in both of these cups are in the same horizontal plane.

A ball-valve 8 is secured on the lower end of a rod or wire 9 pivotally suspended from the connected bar at the point 10. The ball 8 is preferably made of bronze or brass and machined or ground perfectly true. A hole is drilled through the ball, the size of the wire 9, and the latter extended through the ball a short distance and the ball is soldered at this point, pains being taken to prevent the solder from getting on that part of the ball which serves as a valve. The numeral 11 represents the valve-seat.

B, represents the burner, and the numeral 75 12 is the usual needle-valve operating in the valve chamber 13. T, is the oil tank, and the numerals 14 and 14' represent elbows for connecting the pipes 15 leading from the tank to the center of the oil chamber, as shown in Fig. 1.

In assembling the parts, the burner B and needle-valve 12 are first screwed into the upper part of the oil chamber, as shown at the threads 16, and the oil cups 4 are 85 similarly assembled at the outer ends of the oil chamber. The floats 5 with wires 6 attached are next placed in the oil cups, the wires extending down through into the oil chamber where they are pivotally connected to the opposite ends of the connecting bar 7. The wire 9 for the ball-valve 8 is pivotally connected to the center of the connecting bar as at 10, and this wire is then inserted through the sleeve in the lower part 90 of the oil chamber, and the two oil-chamber parts 1 and 2 can now be bolted together. The lower end of the sleeve forms the seat 11 for the ball-valve 8. The ball-valve is soldered to the wire after the two oil-chamber parts 1 and 2 are bolted together. The pipe fitting 14' forms the oil inlet and is screwed on after the ball is soldered to the wire.

With this construction, the oil level at the 105 burner remains at exactly the same place, regardless of how much the oil chamber may be tilted in any direction, and consequently the flame never varies, which is the desideratum.

The ball-valve 8 is operated at all times by both floats through the medium of the connecting-bar 7 sustained and supported by these floats, and by adjusting the floats on their wires or rods 6 the position of the valve 8 with relation to the valve-seat 11 may be regulated.

Thus it will be noticed that both the ball-valve and the needle-valve are at points below the burner, and in the form of the invention illustrated the needle-valve is located between the burner and the ball-valve, one valve above, and the other below the oil-chamber.

15 In this way a simple and most efficient means is provided for controlling the flow of oil in oil-burning brooder-heaters, regardless of any tilting of the oil chamber.

The oil level method of control might be 20 employed when so desired instead of the needle-valve by merely raising and lowering the burner in relation to the oil chamber by any approved means. The foregoing tandem float in fact solves the problem of practical and safe oil level flame control. The methods hitherto employed are dangerous because the entire heater must be set and kept level; in other words, a slight springing or warping of the floor will flood the 25 burner.

Although the burner B is shown as being rigidly secured to, and carried by, the part 1 of the float or oil chamber, it is obvious that it might be adjustable thereon, or otherwise 30 connected therewith, but so that it will tilt with this chamber.

I claim:

1. A device of the character described including a float chamber, a plurality of floats 40 therein, a valve for controlling the supply of liquid to the float chamber and means flexibly connecting the floats together, and connected with said valve for maintaining a substantially constant level of liquid in 45 the float chamber, both when said float chamber is in its normal position and in substantial deviations in any direction therefrom.

2. A device of the character described including a float chamber, a plurality of floats 50 therein, a burner, and means connected with the floats for maintaining a substantially constant level of fuel at the burner both when the float chamber is in its normal position and in substantial deviations in any direction therefrom.

3. A device of the character described including a float chamber, a plurality of floats 60 therein, a burner connected with the float chamber to tilt therewith, and means connected with the floats for maintaining a substantially constant level of fuel at the burner both when the float chamber is in its normal position and in substantial deviations in any direction therefrom.

4. A device of the character described including a burner, a float chamber, a plurality of floats therein, a valve for controlling the supply of fuel to said burner, and means connected with the floats and flexibly connected with said valve for maintaining a substantially constant level of fuel at the burner both when the float chamber is in its normal position and in substantial deviations in any direction therefrom. 70

5. A device of the character described including a float chamber, a plurality of floats therein, a burner connected with the float chamber, a valve for controlling the supply of fuel to said burner, and means connected with the floats and pivotally connected with said valve for maintaining a substantially constant level of fuel at the burner both when the float chamber is in its normal position and in substantial deviations in any direction therefrom. 80

6. A device of the character described including a float chamber, a plurality of floats therein, a burner rigidly connected with the float chamber, and means connected with the floats for maintaining a substantially constant level of oil at the burner, both when the float chamber is in its normal vertical position and in substantial deviations in any direction therefrom. 90

7. A device of the character described including a float chamber, a plurality of floats carried therein, a burner rigidly connected with the float chamber, a valve controlling the supply of oil to the burner, and means connecting the floats with the valve for maintaining a substantially constant level of oil at the burner both when the float chamber is in its normal vertical position and in any substantial deviation in any direction 100 therefrom.

8. A device of the character described including a burner, a plurality of floats maintained in substantial horizontal alignment with the burner both when the burner is in its normal position and in substantial deviations in any direction from such normal position, and means connected with the floats for controlling the flow of oil to the burner. 110

9. A device of the character described including a burner, a float chamber, a plurality of floats in said float chamber maintained at all times in substantial horizontal alignment with the burner, both when the burner is in its normal position and in substantial deviations in any direction from such normal position, and means connected with and operated by the floats for controlling the supply of oil to the burner. 115

10. A device of the character described including a burner, a float chamber, floating means therein, a valve for controlling the supply of fuel to the burner, a bar connected with said valve and means depending from said floating means at a plurality of points 125

- and connected with said bar adjacent the outer ends thereof, forming flexible connections between the bar and the floating means for maintaining a substantially constant 5 level of fuel at the burner, both when the float chamber is in its normal position and in substantial deviations in any direction therefrom.
11. A device of the character described 10 including a burner, a plurality of floats, a valve for controlling the supply of oil to the burner, and means flexibly connected with the floats and with the valve for maintaining a substantially constant level of oil 15 at the burner regardless of the tilt of the device.
12. A device of the character described including an oil supply tank, a plurality of 20 communicating oil cups, means for supplying oil from the supply tank to the oil cups, a burner mounted between the oil cups, floats mounted within the oil cups and being flexibly connected together, and means connected with and operated by said flexible connection for controlling the flow of oil to the oil cups.
13. A device of the character described including an oil supply tank, a plurality of oil cups communicating with each other and 30 forming a float chamber, a burner mounted between the oil cups and substantially equidistant therefrom, floats mounted within the oil cups, a connecting bar having a pivotal connection with said floats, a valve pivotally connected with the connecting bar for controlling the flow of oil to the oil cups, and maintaining a substantially constant oil
- level in the burner regardless of the tilt of the device.
14. A device of the character described 40 including a float chamber, a burner rigidly secured to said float chamber, floats mounted within the float chamber, a valve for controlling the supply of oil to the burner, a bar connected with said valve, and means 45 for flexibly connecting the ends of said bar with the floats for maintaining a substantially constant level of oil at the burner, both when the float chamber is in its vertical position and in any substantial deviation in any direction from such vertical position.
15. A device of the character described including an oil supply tank, a plurality of oil cups communicating with each other 55 forming a float chamber, a burner rigidly connected with the float chamber and substantially equidistant from the oil cups, floats mounted in the oil cups, a valve for controlling the supply of oil to the burner 60 and being located at a point immediately below the oil inlet therefor, a bar to which the valve is connected, and means extending downwardly from the floats and pivotally connected with the bar for operating the 65 valve from the floats to maintain a substantially constant level of oil at the burner, both when the float chamber is in its vertical position and in any substantial deviation in any direction from such vertical 70 position.

In testimony whereof I affix my signature:

HENRY M. SHEER.
